DISPLAY FIGURE

Nellie Spotts Ellsworth, San Francisco, Calif.

Application May 25, 1934, Serial No. 727,415

7 Claims. (Cl. 46—157)

This invention relates to display figures and has for its objects such figures respectively made from a single sheet of flat material, including a supporting base, and which figures are formed to simulate objects in three dimensions.

Other objects will appear in the specification and drawing.

Fig. 1 is a front view of a blank of sheet material preparatory to folding to form a figure.

10 Fig. 2 is a reduced view of the blank of Fig. 1 in the process of folding to form the figure.

Fig. 3 is an enlarged front view of the blank of Fig. 1 completely set up.

15 Fig. 4 is a sectional view of Fig. 3 taken along the line 4—4 of Fig. 3.

Fig. 5 is a front view of a blank of sheet material for forming another figure.

Fig. 6 is a reduced view of the blank of Fig. 5 in the process of folding to form the figure.

20 Fig. 7 is a view of Fig. 6 in a slightly further stage of folding.

Fig. 8 is a view of the blank of Fig. 5 completely set up.

25 Fig. 9 is a sectional view of Fig. 8 taken along the line 9—9 thereof.

Fig. 10 is a reduced rear view of the head of Fig. 8.

In detail, Fig. 1 is a blank of semi-rigid sheet material adapted to be folded to simulate a 30 female figure, which blank comprises a base 1, and body portions generally designated 2, 3, extending respectively oppositely from two opposite edges of the base.

The body portions 2, 3 are foldable along lines 35 4 to bring the two portions in opposed relation with said portions extending generally vertically perpendicularly to the base with the feet of the respective body portions connecting with the opposite edges of the base and legs 5, 6 on each 40 portion respectively, extending outwardly therefrom.

Although part of the body portion 3, particularly the legs and head, are adapted to form a portion of the front of the body when folded, it 45 will be seen that the greatest part of the figure when viewed from the front, is a portion of the body portion 2, therefore in distinguishing between the body portions in the description, I will designate the portions 2 as the "front body portion" and the portion 3 as the "rear body portion."

The legs of the rear body portion are provided in outward extension thereof, in order, with a trunk 7, rear head portion 8 and a face head portion 9, the latter adapted to be folded forwardly over the rear head portion as will later be described. Trunk 7 is provided with laterally projecting arms 10 extending outwardly of the opposite side edges thereof.

50 The front body portion is formed with a semi-

circular skirt 11 and a trunk 12, said skirt and trunk being positioned transversely of the longitudinal axis of the body before being folded, the legs connecting with the peripheral edge of the skirt at one end of the hemispherical portion. 5

In folding the blank of Fig. 1 the lowermost portion of the blank as seen in said figure or body portion 2, is folded rearwardly behind body portion 3, best seen in Fig. 2, to bring the front and rear body portions in substantially opposed relation and the skirt 11 is then bowed around the front side of the body 3. This produces a sort of inverted funnel-shaped skirt with the lower edge well spaced from the body and brings the trunk 12 around to the front side of the trunk 7 of the body 3, in reality making the greater portion of the skirt and all of trunk 12 the front part of the figure.

The trunk 12 and skirt are retained in this front position by means of a tab 13 on the free end of the skirt engaging in a slot 14 formed in that portion of the skirt that is adjacent the point of attachment of the legs 5 with said skirt, this tab and slot connection being in the rear of the figure, hence not visible from the front. Fig. 2 25 illustrates the folding steps above described.

The trunk portion 12 is slightly longer and wider than trunk 7 on the body portion 3 and I provide a tab 17 at the upper edge of trunk 12 and a slot 18 adjacent the neck of trunk 7, so that 30 outwardly bowing the trunk 12 from the waist to the neck, the tab 17 will engage in slot 18 and the bust of the figure will be simulated in contour when the figure is viewed from the side.

The next step in forming the figure is the forming of the head. The head portion 8 and the face head portion 9 are each provided with ears 20, 21 at their opposite side edges respectively, and vertically extending slots 22, 23 are provided at the junction of ears 20, 21 respectively with the 40 head portions, said slots extending downwardly from the upper edges of the connection between the ears and head portions before folding of the face head portion over the portion 8.

The face or front head portion 9 is larger in 45 width and height than the rear head portion 8, so that when portion 9 is bent forwardly and downwardly along line 19 over the rear head portion, and the ears are interlocked at slots 22, 23, the face portion of the head is bowed outwardly 50 as best seen in Fig. 4 and is spaced away from the front surface of the portion 8, thereby giving the head as well as the bust and skirt a three dimensional appearance.

The exposed rear and front surfaces of the 55 front and rear body portions are imprinted with surface printing to indicate the features of clothing, etc., and when folded the bowed and overlapping parts are adapted to coact with all other portions of the figure to complement the printing 60

on said other portions, such imprinting not being extensively indicated in order to avoid as much as possible confusing the structural features with such printed matter.

- 5 Figs. 5 to 10 indicate a male figure in various views. This figure comprises a base 1', a rear body portion generally designated 3', and front body portion 2', said front and rear body portions extending oppositely from opposite edges 10 of base 1' and bendable at 4' at the opposite edges of said base to bring the body portions 2', 3' into a generally opposed relation extending substantially perpendicular to the plane of the base portion, best indicated in Fig. 7.
- 15 The two body portions of this figure are also provided with legs 5', 6', the same as in the female figure, but instead of providing the rear body portion 3' with arms as in Figs. 1 to 3, I provide arms 10' on the opposite lateral edges of 20 the front portion only. The trunks of rear and front body portions of the male figure, respectively designated 7' and 12' extend longitudinally outwardly of the legs and the rear body portion is formed along its lateral edges with 25 outwardly projecting extensions 25 simulating the outline of a coat.
- 30 The rear body portion 3' of the male figure has an elongated relatively narrow neck portion 26, and a large head portion 9' that is adapted to fold forwardly over the neck portion 26 along the line 19'.

The front body portion 2' has a bust or upper trunk portion 27 and a transverse slot 28 is provided at the waist of the front body member. 35 When the front and rear body portions are in opposed relation the elongated portion 27 is folded along the line 29 of the figure and a tab 30 on the outer end portion 27 is engaged in slot 28, the portion 27 being bowed outwardly to 40 form the bust and the front and rear body portions being in engagement with each other at a point behind the bowed portion 27. In order to hold the two portions 2', 3' together and to properly simulate the male figure, I provide slots 32 on the rear portion 3' that are spaced on either 45 side of a medial line extending longitudinally of said portion 3' at points to pass the arms 10' therethrough, as best seen in Figs. 6, 7. The coat projections 25 are then bent forwardly along lines 33, to give a coat appearance when the figure is viewed from the side, as seen in Fig. 7.

The head portion 9' of the male figure, instead of engaging at the sides as in Figs. 1 to 3, is provided with lateral extensions 34 having tabs 35 that interlock behind the neck 26 through 50 slot 36 in the neck, the face of the head being bowed outwardly as seen in Fig. 9. Ears 37 are cut in the head 9' on opposite sides along the fold lines 38 of the extensions 34, which project laterally to simulate the ears of the head, 55 as best seen in Fig. 8.

Other forms can, of course, be provided, such as animals of the lower classes, fowls, etc., but the features of wrapping one portion around another to form the head or body of the figures, 60 and the insertion of arms of one body portion through the other to secure the parts in position, and the provision of opposed body portions, all arranged to simulate a display figure in three dimensions, are thought new and novel irrespective of the surface characteristics of the figures.

Having described my invention, I claim:

1. A display figure of semi-rigid sheet material comprising a pair of opposed members extending generally vertically, one of said members having outlined edges generally simulating

the outline of a specific object when viewed from the front, and the other member shaped to simulate the contour of a substantial portion of the upper half of such object when viewed from the side. 5

2. A display figure of semi-rigid sheet material comprising a pair of opposed members extending generally vertically, one of said members provided with an extension at a point spaced above the lower end thereof, said extension being outlined and shaped to coact with said opposed member to define a portion of the contour of the figure when viewed from the side. 10

3. A blank of semi-rigid material shaped and adapted to be folded to form a figure simulating 15 an animal, which blank when folded provides spaced supporting legs and a body portion and a head portion, said body portion comprising a pair of opposed members, one of which members is provided with extensions projecting outwardly 20 from opposite edges thereof and the other member being provided with a pair of slots adapted to receive said extensions therethrough for securing the said members together and said extensions being shaped to simulate portions of the 25 figure of the animal and the head portion of the figure comprising an extension of one of said members.

4. A blank of semi-rigid sheet material shaped and adapted to be folded to form a figure simulating 30 the human form, which blank when folded provides a supporting base and a pair of opposed members adapted to form the body of the figure, one of said opposed members being longitudinally extended to provide a head portion, and the other of said members being bowed outwardly 35 from the waist to the neck portion of the figure to simulate the bust of a human form in contour when viewed from the side of the figure as distinguished from a front view thereof. 40

5. In a construction as defined in claim 4, an extension formed on one of said opposed members adapted to be bowed across the outer lateral edge of the opposite member with a portion 45 of said extension spaced therefrom for simulating the contour of a portion of the clothing of the figure when the figure is viewed from the side as distinguished from a front view of the figure.

6. A blank of semi-rigid sheet material shaped and adapted to be folded to form a figure simulating 50 a human form, which blank when folded provides a pair of opposed complementarily formed body portions spaced from each other at the feet to provide a base and one of said body forms being provided with a portion adapted to 55 be bowed outwardly from the waist to the neck for simulating the contour of a human form when viewed from the side and means for securing said portion in bowed position.

7. A blank adapted to be folded to form a figure 60 simulating a specific object, which blank when folded provides a pair of opposed generally vertically extending front and rear members spaced at the bottom to provide a supporting base, one of said opposed members being 65 provided with extensions on opposite side edges thereof adapted to be folded toward the opposite member and means connecting said extensions with the opposite member for retaining the front and rear members in spaced relation 70 with the extensions forming the sides of the object for simulating the contour of the specific object when viewed from the side thereof.
